poration of Delaware
Filed Dec. 17, 1962, Ser. No. 245,258
1 Claim. (Cl. 206—1)

This invention relates to an improved shipping container for fragile klystron tube grids, especially one that permits easy visual inspection of the grids before and after shipment.

Klystron tube grids are quite small and fragile. They are usually round with a diameter of $\frac{1}{8}$ to $\frac{5}{16}$ inch and a thickness of 0.005 to 0.020 inch. The grids have an outer containing ring which contains elements in the form of spokes, vanes, honeycomb structure and the like. The outer ring may have a wall thickness as low as 0.010 inch and the elements usually have a thickness in the order of 0.005 to 0.0015 inch. Copper is a metal customarily used to fabricate the grids and it is usually annealed during the manufacturing procedure.

Inspection and shipment of grids in quantity without damage has been a serious problem. Careless and unnecessary handling usually results in breakage. Looseness or rattling in the shipment container has been known to cause the grids to become out of round.

The shipping container of the present invention is of a simple inexpensive rugged design that securely holds numerous grids and permits ready visual inspection of the grids before and after shipment without the necessity of removing them from the container.

The drawing attached to and forming a part of this specification is an exploded perspective view of the klystron tube grid shipping container.

Referring to the drawing, the shipping container comprises a rigid flat base 1 preferably of a plastic such as a polyethylene or polystyrene about $\frac{1}{8}$ inch thick. The base can have any shape but round is preferred because it permits center hold down without the top swiveling

2

out of alignment. The base may have a shoulder (not shown) encompassing the lid or cover, or the cover may have a downturned edge (not shown) to encompass the base. The base is preferably opaque such as white or black so that the grids will visually stand out.

One face of the base has numerous indentations 2 matching the size of the grids to be contained therein and having a depth equal to that of the grids.

The mating top cover 3 consists of a transparent rigid material such as a polystyrene, glass or an acrylate about $\frac{1}{16}$ inch thick. It fits flush against the face of base 1 and thus snugly holds the grids in place. While other means of attaching the top cover can be used such as hinges or clamps, a central thumb screw 4 is preferred because of its simplicity and effectiveness and because of its contribution to the over all appearance of the holder. Central hold down with the round shape assures that the cover can not swivel out of place.

Having described this invention, what is sought to be protected by Letters Patent is succinctly set forth in the following claim.

What is claimed is:

A klystron tube grid shipping container comprising a rigid flat circular opaque base, the upper surface thereof being provided with a plurality of compartment recesses having a size and shape corresponding to and receiving klystron tube grids therein, and a mating rigid transparent cover fitting tightly against said upper surface of said base closing said recesses and secured to said base with a centrally located hand demountable means, said cover permitting visual inspection of said klystron tube grids therethrough.
